UNITED STATES PATENT OFFICE.

FRANK H. STANWOOD, OF CHICAGO, ILLINOIS, ASSIGNOR TO STANWOOD EQUIPMENT COMPANY, OF CHICAGO, ILLINOIS, A CORPORATION OF MASSACHUSETTS.

STEP PLATE.

1,420,776.

Specification of Letters Patent. Patented June 27, 1922.

Application filed August 20, 1919. Serial No. 319,664.

To all whom it may concern:

Be it known that I, FRANK H. STANWOOD, a citizen of the United States, residing in Chicago, in the county of Cook and State 5 of Illinois, have invented a new and useful Improvement in Step Plates, of which the following is a specification.

This invention relates in general to safety step plates for automobiles and the like and 10 has for its object the provision of a safety step plate of new and improved construction adapted to be fastened in place upon the running board of the automobile without the necessity of providing special tools 15 or implements, and also without requiring particular or complicated instructions for the installation.

Another important object of the invention is the provision of a step plate of the 20 character described which will be so constructed that the parts subject to greatest wear may be readily removed and replaced and the remaining parts permanently protected against marring, damage in use and 25 rapid deterioration.

The invention has for a further object the provision of a step plate of the character described of pleasing and novel appearance, of unusually durable quality and 30 which may be cheaply manufactured.

Numerous other objects and advantages of the invention will be apparent as it is better understood from the following description when considered in connection 35 with the accompanying drawing illustrating a preferred embodiment thereof.

Referring to the drawing,

Figure 1 is a perspective view of a step plate embodying my present invention;

40 Fig. 2 is a bottom plan view thereof, parts of the ribs being broken away.

Fig. 3 is a section taken substantially on the line 3—3 of Fig. 1; and

45 Fig. 4 is a section taken on the line 4—4 of Fig. 1.

My present invention is shown on the drawings as embodied in a step plate consisting of a metal plate 11 of suitable size and shape and having two sets or series of 50 parallel slots 12, this plate being covered entirely with rubber or other yielding or vulcanizable material, and having yielding tread ribs 13 of rubber or the like disposed through the slots.

The material of the sheet is pressed up 55 at 14 about the slots to provide upstanding and slightly inwardly extending walls and a continuous coating of rubber 15 is over all of the metal of the sheet. The ribs 13 each comprise an upstanding body and have 60 at each side at the bottom a laterally projecting foot or extension 17 which preferably also extends beyond the end of the rib so that the rib is provided with a continuous foot extending about it. 65

The ribs are pushed through the slots from beneath and are frictionally held in place, the feet 17 aiding in preventing the ribs being pulled out of the slots when the step plate is in position upon the running 70 board of an automobile and the tightness of fit between the rib and rubber covered slot wall, which walls may if desired press into the rubber of the rib, prevents dislodgment of the ribs after assembly and until 75 they are in position for use. It will of course be understood that these step plates are made up as shown on the drawing and furnished to the trade in this condition, and it is particularly desirable that the ribs be 80 securely held in place prior to affixing them in permanent location, to the end that no assembling may be necessary in such operation and to the further and perhaps more important end that there shall be no need 85 of individually holding the ribs in place in the slots at the time the plate is placed upon the running board.

The rubber or like coating of the plate does not scratch or mar and is preferably 90 vulcanized to the metal. This may be accomplished by putting a thin film of copper on the plate before it is placed in the mold with the rubber. The rubber coating therefor provides a permanent protection for the 95 plate and since the ribs receive substantially all the wear replacement of worn parts is easy and quickly accomplished. This may be done by merely removing the plate from the running board, taking out the worn 100 ribs, inserting new ones in their place and repositioning.

It will be noted that the rubber coating of the metal body not only prevents marring and rusting of said body but also provides means for effectually holding the inserted ribs during transit handling and until actual application to the running board. 105

It is thought that the invention and many of its attendant advantages will be understood from the foregoing description, and it will be apparent that various changes 5 may be made in the form, construction and arrangement of the parts without departing from the spirit and scope of the invention or sacrificing all of its material advantages, the form hereinbefore described being 10 merely a preferred embodiment thereof.

I claim:

1. A safety step plate for automobiles and the like, comprising in combination a slotted plate having a protective yielding coating 15 and yielding ribs disposed through the slots of said plate and protruding above said plate.
2. A safety step plate for automobiles and the like, comprising a metal sheet coated 20 with a material vulcanized thereto, and having slots disposed therethrough, and ribs of similar material disposed through the slots and protruding thereabove.
3. A safety step plate for automobiles 25 and the like, comprising a slotted metal plate covered with a protective yielding

coating and yielding ribs extending up through the slots and having laterally extending feet or projections at their sides disposed beneath said plate. 30

4. A safety step plate for automobiles and the like, comprising a metal plate having slots surrounded by upstanding walls and covered with a protective yielding coating, and yielding ribs thrust therethrough 35 from beneath and having laterally extending projections or feet disposed beneath said plate.

5. A safety step plate for automobiles and the like, comprising a slotted metal 40 sheet entirely encased in rubber and rubber ribs insertable through the slots of said sheet and protruding thereabove, and means beneath the sheet for holding said ribs against removal. 45

6. A safety step plate for automobiles and the like, comprising a metal sheet having slots surrounded by upstanding walls, rubber covering said entire sheet, and rubber ribs having lateral extensions at their bottoms and disposed through said slots. 50

FRANK H. STANWOOD.
